YARN CARRIER ROD CONTROL MECHANISM
FOR KNITTING MACHINESHenry C. Pingel, Wyomissing, Pa., assignor to
Textile Machine Works, Wyomissing, Pa., a
corporation of Pennsylvania

Application April 25, 1951, Serial No. 222,831

14 Claims. (Cl. 74—112)

1

This invention relates to an apparatus for operating the stops for yarn carrier bars for laying reinforcing yarns in making full-fashioned knitted fabric.

The stops for controlling the width of reinforced knitted areas along the selvages of full-fashioned fabric have commonly been operated by a mechanism including a spindle known as the reinforced selavage spindle, and pawls for reversely rotating said spindle, the pawls being actuated by a single connection from a cam lever, one pawl on the upstroke of the connection and the other pawl on the downstroke of the connection. The downstroke has been caused by a cam on the main cam shaft and the upstroke caused by spring action. This mechanism has also included a cam means normally holding one pawl out of operation while permitting the other pawl to operate, the cam means being operated at times from the ordinary pattern chain of the machine to hold the other pawl out of operation and to permit the one pawl to operate. The cam means is returned to normal position by spring action.

However, this cam means becomes jammed at times during its operating movement to prevent its return to normal position by the spring action, thereby defectively operating the reinforced selavage spindle. It is an object of the invention to provide a mechanism for operating a reinforced selavage spindle which shall be entirely free from this difficulty.

A further object of the invention is to provide a reliable, efficient and long lived mechanism for racking a spindle in either direction as desired.

Another object of the invention is to provide a discriminating mechanism adapted to reverse the direction of rotation of a racked spindle and which is free of any spring of a size rendering the mechanism subject to jamming.

With these and other objects in view, which will become apparent from the following description of the illustrated embodiment of the invention shown in the accompanying drawings, the present invention resides in the novel elements, features of construction and arrangement of parts in cooperative relationship as hereinafter more particularly pointed out in the claims.

In the drawings:

Figure 1 is a sectional elevation of a known type of full-fashioned knitting machine having the invention applied thereto and embodied therein, parts being omitted;

2

Fig. 2 is a detail plan view, partially in section, taken substantially on the line 2—2 of Fig. 1 looking in the direction of the arrows;

Fig. 3 is an elevational view taken from the left of Fig. 1 with parts being omitted;

Fig. 4 is an elevational detail view of a portion of the mechanism taken from the right of Fig. 3, parts being omitted and others shown in section;

Fig. 5 is a detail view taken substantially on the line 5—5 of Fig. 1, looking in the direction of the arrows, parts being broken away and others in section;

Fig. 6 is a detail elevational view of certain of the parts shown in Fig. 3;

Fig. 7 is a detailed view of a portion of Fig. 6, parts being broken away and others shown in section;

Fig. 8 is a view taken substantially on the line 8—8 of Fig. 1, looking in the direction of the arrows, parts being in section;

Fig. 9 is a detail view similar to a portion of the mechanism shown in Fig. 1, parts being broken away and other parts being omitted for purposes of illustration;

Fig. 10 is a detail view similar to Fig. 9, parts being omitted, other parts being further broken away and certain parts being shown in different positions from the ones in which they are shown in Fig. 9;

Fig. 11 is a view similar to Figs. 9 and 10, parts being broken away and certain parts being shown in the same positions as in Fig. 9, Fig. 11 showing however, parts omitted in Figs. 9 and 10;

Fig. 12 is a view similar to Fig. 9 but with more parts broken away to show a second mechanism, one generally similar to that of Figs. 9 and 10, which lies behind the parts shown in Fig. 9; and

Fig. 13 is a view generally similar to Fig. 12 but further broken away and certain parts shown in different positions from the ones in which they are shown in Fig. 12.

In the drawings and description, only the means necessary to a complete understanding of the invention are specifically set forth; further information as to the construction and operation of other related, usual and well known knitting machine elements, mechanisms, etc., may be found in one or more of the following publications:

1. Pamphlet entitled—Full-Fashioned Knitting Machines—published and copyrighted by the Textile Machine Works, Reading, Pennsylvania, in 1920.

2. Four catalogs entitled—The "Reading" Full-Fashioned Knitting Machine Parts Catalog—published and copyrighted by the Textile Machine Works, in 1929, 1935, 1940 and 1947, respectively.

3. Booklet entitled—The "Reading" High Production Full-Fashioned Knitting Machine—which, forming a supplement to the above noted 1940 Parts Catalog of the Textile Machine Works, is a publication of the Textile Machine Works, copyrighted by the latter in 1940.

4. Pamphlet entitled—Knitting Machine Lectures—published by the Wyomissing Polytechnic Institute, Wyomissing, Pennsylvania, in 1935.

An apparatus according to the invention comprises a pair of trains of mechanism, each train biased in a certain direction and a cam and follower means arranged to hold said trains against their bias but acting to release them at desired times, together with a discriminating means adapted to prevent either one of said trains from operating at the time of any given operation of the cam and follower means.

In the arrangement shown, the two trains of mechanism are employed to turn a spindle in either direction as desired. It is therefore desirable to have two oppositely inclined ratches on the spindle and to provide pawls for the ratchets normally in contact therewith to hold the spindle against undesired movements. Also, cam or bluff means is provided to lift a first pawl from its ratchet when a second pawl is to operate its ratchet and to lift the second pawl from its ratchet when the first pawl is to operate its ratchet. Preferably, the racking pawls are free of the bluffs when inactive and also act as holding pawls when the trains are inactive. According to the invention, the individual trains of mechanism are connected each to portions of the cam means individual thereto so that when one train actuates one pawl the portion of the bluff means connected thereto not only disables the other pawl but, due to the inelastic character of the connection, returns the bluff portion to the same inactive position from which it started and without any substantial chance of its jamming in a wrong position.

It will be seen that there is a discriminating action at two different points, one at the points at which the trains receive impulses and one at the points at which they deliver them.

Referring to the drawings and particularly to Fig. 1, the invention is shown applied to a full-fashioned knitting machine having a usual framework including center frames 15, a front beam 16, back beam 17 and a front bed 18. The framework also includes end frames and a center bed (not shown) and carries a cam shaft 20 on which is mounted a cam 22 for initiating impulses for turning a threaded spindle 24 of a usual reinforced selvage attachment. The reinforced selvage attachment shown is the one near the left end of the machine for controlling the inner position of the yarn carriers for the left reinforced area of a stocking blank, as viewed from the front of the machine. It is to be understood that a similar attachment is provided near the right end of the machine for controlling the inner position of the yarn carriers for the right reinforced area of the stocking blank. Both left and right attachments, except that they are of opposite hand, are identical in structure and are operated simultaneously to position the yarn carrier stops closer or further from each other so that a description

of the left attachment shown will also suffice as a description of the right attachment.

The spindle 24 carries a nut 25 (Fig. 3) which is provided with stops (not shown) against which the carrier rod or rods for the left reinforcing yarn carriers abut at the inner end of their travel.

An impulse from cam 22 for turning spindle 24 is transmitted to the spindle by mechanism including a follower 28 mounted on a lever 30 pivoted intermediate its ends on a pin 31 carried in a bracket 32 on the back beam 17. The pin 31 is at the left of follower 28 and the lever 30 is biased to turn clockwise as viewed in Fig. 1. The cam 22 has a high and a low portion, the follower 28 being moved up and down whenever it is free to follow the contour of the cam. As it is desired to maintain the spindle 24 stationary during the majority of the revolutions made by the cam shaft 20 for making a given stocking blank, a lever 34 is provided to normally support the right hand end of lever 30, as viewed in Fig. 1, in the position to which it is raised by the high point of the cam. Due to the right end of lever 30 resting on the upper end of lever 34 as shown, spindle 24 remains stationary until lever 34 has been moved to release lever 30. For so moving lever 34, the lever is pivoted on a fixed axle 36 and its lower portion is adapted to be operated at desired times by a pattern means of known form indicated somewhat generally at 40. Pattern means 40 is to be assumed as including a pattern chain running on sprocket drum 41. A button on the chain operates to swing lever 34 clockwise as viewed from the right of Fig. 1 to carry to upper end of lever 34 out from under the right hand free end of the lever 30. The previously mentioned bias of lever 30 causes the lever to oscillate down and up as the follower 28 follows the contour of the cam from the high point of the cam to the low point and back. The means for biasing lever 30 is provided in the arrangement shown as an incident to the trains of mechanism A and B (Figs. 1 and 4) for transmitting impulses from the cam 22 to the spindle 24.

The trains of mechanism A and B each comprise one of a pair of lever members 44 and 45, respectively, pivoted on the pin 31 and arranged one on one side and one on the other side of an arm 42 of lever 30 which extends to the left of pin 31. Arm 42 has lugs or ears 46 thereon, shown in Figs. 1 and 2, which extend from the arm above members 44 and 45 and which have contacts shown as set screws 48 threaded therethrough in positions to contact upper surfaces of members 44 and 45. Springs 50 are associated with the train lever members 44 and 45 so as to urge them clockwise as viewed in Fig. 1, the springs being in tension and connected at their lower ends to members 44 and 45 and at their upper ends to fixed portions of the frame. The tension of springs 50 therefore holds the members 44 and 45 against set screws 48 thereby tending to turn lever 30 clockwise and holding follower 28 in contact with cam 22. Clockwise movements of follower lever 30 and train lever members 44 and 45 therefore are spring actuated while their counterclockwise movements are positive power actuations caused by the cam 22, as the follower 28 moves from the low to the high portion of the cam. There being two train levers 44 and 45, each a part of a train of mechanism for transmitting an impulse caused by such an oscillation, it is necessary to provide a discriminating means to determine which train

of mechanism is to transmit a given cam impulse to spindle 24. It is to be understood that an impulse from the cam delivered through one train of mechanism turns the spindle oppositely to a cam impulse delivered through the other train of mechanism.

For this purpose, the arrangement shown in the drawings has a pair of levers 52 and 54 which are mounted, according to the arrangement shown, to swing in a vertical plane transverse to the planes of movement of levers 44 and 45 as best shown in Figs. 2, 3 and 5. Levers 52 and 54 are pivoted on pins 53 and 55, respectively, on a bracket 56 which is fixedly secured to the frame of the machine. Levers 52 and 54 are coupled together by a horizontal link 58, pivoted to each of levers 52 and 54 at points 57 and 59 respectively, so that levers 52 and 54 must swing on their fixed pivots in synchronism. At their lower ends, levers 52 and 54 have shallow notches 60 and 61, respectively, each of the notched ends being adapted to swing back and forth above flat surfaces 62 and 63 on levers 44 and 45, respectively. The levers 52 and 54 are so arranged, that when lever 54 overlies the surface 63 on lever 45, as shown in Fig. 5, lever 52 is out of the path of the surface 62 on lever 44 and when lever 52 overlies the surface 62, lever 54 is out of the path of surface 63 of lever 45. Means is provided whereby link 58 is biased to hold lever 52 normally out of the path of surface 62 of lever member 44, Figs. 3 and 5, and to hold lever 54 so that its notch 61 overlies the surface 63 on lever 45. However, link 58 is adapted, at desired times, to swing levers 52 and 54 so as to reverse their positions relative to levers 44 and 45, so that flat 62 on lever 44 will engage in notch 60 of discriminating lever 52. The means for holding link 58, and consequently the levers 52 and 54, in the position shown in Figs. 3 and 5 comprises a second pattern operated lever 64 shown alongside lever 34 and adapted and arranged to be operated by buttons on the usual pattern chain (not shown) of the pattern means 40. Lever 64, when operated by the pattern means, swings against a flange 68 which depends from a lever 70 which is fixed at the end of a shaft 72 journaled in brackets fixed to the machine frame so that the shaft extends from the front to the back of the machine, as is clear from Fig. 1. At its rear end, the left hand end as shown in Fig. 1, shaft 72 has fixed thereon an arm 74 (Figs. 3 and 5) which engages a pin 76 fixed to link 58.

Pattern lever 64 has a laterally extending plate 78 thereon, so that, when lever 64 is operated by the pattern means, the lever 34 is also operated without an additional adjustment of the pattern means for this purpose. The purpose of this joint operation of levers 34 and 64 is to cause an impulse from cam 22 to be transmitted through the train of mechanism of which lever 45 is a part instead of through the train of which lever 44 is a part. The normal positions of discriminating levers 52 and 54 being as shown in Fig. 5, when shaft 72 is turned by lever 64, arm 74 is turned clockwise as viewed in Fig. 5 and thereupon a tension spring 80, connected between link 58 and the arm 74, draws discriminating levers 52 and 54 also clockwise about pins 53 and 55, respectively, to swing the lever 54 away from lever 45 and to swing lever 52 above lever 44 so that the train having lever 45 therein is free to operate and the train having lever 44 therein is prevented from operating. It is feasible to use an arrangement of this character because the

initial movements of members 44 and 45 away from the position shown in Figs. 1, 3 and 5 are spring actuated and the levers 52 and 54 merely hold one or the other of levers 44 and 45 against movement by one or the other of springs 50 without interfering in any way with the motion of follower lever 30 or the cam 22. As soon as the pattern means releases the flange 68 by returning lever 64 to inactive position the shaft 72, arm 74 and the discriminating levers 52 and 54 are returned to the positions shown in Fig. 5 by a tension spring 82 which is connected between a pin 84 fixed on bracket 56 and the arm 74.

From the foregoing description it will be seen that when lever 34 alone is operated to release follower lever 30, lever 44 operates while lever 45 and its train are not affected. The lower ends of levers 34 and 64 are connected in the usual manner (not shown) to rods 83 which extend along the machine and are connected to levers similar to levers 34 and 64 for operating the aforementioned right selvage attachment. Therefore, when the pattern means operates lever 34 or levers 64 and 34, as hereinbefore set forth, to control the rotation of the left spindle 24, the rods 83 operate similar levers to cause a corresponding movement of the right spindle.

Pivoted connected to each of levers 44 and 45, respectively, by pins 86 and 87 are links 88 and 89, the upper ends of which are connected to similar bell-crank levers 90 and 91, respectively, pivotally mounted on a pin 92 carried in a fixed part of the machine. Each of bell-crank levers 90 and 91 have substantially vertically extending arms carrying floating pins 94 (Fig. 1) and 95 (Fig. 4), respectively. It will be seen that as train lever members 44 and 45 swing up and down, the pins 94 and 95 will move back and forth in substantially horizontal lines. Each of pins 94 and 95 has two links pivotally connected thereto and arranged one above the other, links 96 and 98 being pivoted on pin 94 and links 100 and 102 on pin 95. Link 96 is the lower one on pin 94 and link 98 is the upper one. Similarly, link 100 is the lower link on pin 95 and link 102 is the upper one. One of said upper links is pivoted at its end removed from its floating pivot to a lever pivoted on spindle 24. As shown, link 98 is pivoted at 104 to a bell-crank lever 106, best shown in Fig. 9. Lever 106 has pivoted thereto a pawl 108 for racking spindle 24. This pawl cooperates with ratchet wheel 110 fixed on spindle 24 to turn the spindle in the clockwise direction as viewed in Figs. 1 and 9-13. A spring 112 is connected between the pawl 108 and lever 106, to keep the pawl normally in engagement with a tooth of ratchet 110.

Also, the lower link 100 connected to floating pin 95 is shown as pivoted at 114 to a bell-crank lever 116 to which a pawl 118 (Fig. 12) is pivoted. This pawl cooperates with a ratchet wheel 120 fixed on spindle 24 to turn the spindle in the counterclockwise direction as viewed in Figs. 4 and 9-13. A spring 121 (Fig. 8) acts normally to hold pawl 118 in contact with a tooth of ratchet 120.

As pawl 108 acts oppositely to pawl 118 and the teeth of ratchet wheel 110 are opposed to those of ratchet wheel 120 and both pawls are in contact with their ratchets when the spindle 24 is idle, there is no need of holding pawls for spindle 24 but a discriminating means is needed to prevent one pawl from acting as a holding pawl while the other is operating to transmit an impulse from cam 22 to spindle 24. For this

purpose, one of the lower links and one of the upper links connected to the floating pins is connected to a cam or bluff adapted to disable one of the pawls 108 and 118. In the arrangement shown, lower link 96 which is connected to pin 94 is also pivoted at 124 to a cam or bluff means comprising a ring 126 mounted to oscillate about the spindle 24 and having thereon a cam portion 128 acting when pin 94 is reciprocated to disable pawl 118 by contacting a lug 130 (Figs. 9 and 10) on pawl 118. Similarly, the upper link 102 connected to pin 95 is pivoted, at point 134, to cam or bluff means comprising a ring 136 mounted to oscillate about spindle 24 and having thereon a cam portion 138 acting when pin 95 is reciprocated to disable pawl 108 by contacting a lug 140 shown dotted in Figs. 12 and 13, the action of cam portion 138 on lug 140 being most clearly indicated in Fig. 13.

In the cases of both cam portion 128 and cam portion 138, the cam portions are normally in positions free of the lugs 130 and 140 so that both pawls 108 and 118 are in contact with their respective ratchets and the spindle 24 is locked against rotation in either direction. When, however, follower lever 30 is released by the pattern means 49 through the lever 34, shaft 72 being maintained stationary at the time, train lever member 44 swings upwardly, thereby turning bell-crank lever 90 counterclockwise and moving the floating pin 94 leftward as viewed in Fig. 9. Link 98 thereupon turns bell-crank lever 108 counterclockwise about spindle 24 thereby moving pawl 108 in the same direction far enough for it to drop in behind another tooth of ratchet 110 as shown in Fig. 10. Pawl 108 is thereby put in a position to deliver a racking thrust to spindle 24 through ratchet 110 as soon as the motion of floating pin 94 is reversed. At the same time that pawl 108 is so moved counterclockwise, link 96 draws cam portion 128 clockwise about spindle 24 to the position shown in Fig. 10 and in which cam portion 128 holds the tip of pawl 118 just outside the boundary circle of the teeth of ratchet 120. When the movement of floating pin 94 is now reversed, pawl 108 turns the spindle clockwise as viewed in Fig. 10 but pawl 118 remains stationary, cam portion 128 holding the pawl 118 above the teeth of its ratchet 120. However, cam portion 128 moves counterclockwise at the time pawl 108 moves clockwise, as will be seen from Fig. 9, and pawl 118 is dropped by its cam portion quickly enough so that it falls in against the tooth next the one from which it was lifted by the cam portion 128, so that the movement of the spindle 24 is checked by pawl 118 as soon as the spindle has turned an angular distance equal to that of one ratchet tooth. The spindle will then be locked by the two pawls as shown in Figs. 9, 11 and 12.

Similarly, when the train of mechanism which includes train lever member 45 is actuated by cam 22, lever 91 is moved counterclockwise and floating pin 95 is moved leftward, as viewed in Figs. 4 and 12, causing link 100 to turn pawl 118 clockwise far enough for it to drop in behind a different tooth of ratchet 120 (Fig. 13) pawl 108, however, remaining stationary. At the same time pawl 108 is held stationary by floating pin 94, so far as movement about the spindle 24 is concerned, the cam portion 138 is moved counterclockwise about the spindle, thereby lifting pawl 108 and permitting pawl 118 to turn the spindle 24 when the movement of floating pin 95 is reversed by an impulse from cam 22. Also, pawl 108 is

released by its cam portion so that the pawl stops spindle 24 as soon as it has been turned a one tooth distance.

It will be seen from Fig. 8 that cam portions 128 and 138 and their supporting members 126 and 136 lie intermediate the ratchets 110 and 120. Cam portions 128 and 138 are, however, automatically operated and stand when inactive out of contact with the pawls 108 and 118, thereby permitting these pawls to hold the spindle locked, whereas it is desired at times to manually turn spindle 24 to reset the nut 25. In order that the spindle may be so turned, a third cam or bluff means is provided comprising a ring member 142 (Fig. 11) mounted to turn about spindle 24 and carrying two cam portions 144 and 146 adapted to act on the lug 140 on pawl 108 and on lug 130 on pawl 118, respectively, to throw both pawls away from the teeth of their ratchets so that the spindle may be turned by a handle 147 pivotally carried on a shaft 149 in a fixed part of the machine frame (Fig. 1). Normally, cam portions 144 and 146 are held in inoperative positions by a handle 148 on an arm 150 fixed to ring 142. Handle 148 comprises a knob 152 which has a pin 154 (Fig. 11) fixed centrally therein and positioned and adapted to enter either of two apertures in a bracket member 156 carried on a fixed part of the machine frame (Fig. 8) one of said apertures appearing at 158 in Fig. 11. A compression spring (not shown) biases pin 154 in the direction to enter an aperture 158. The pin may be withdrawn from an aperture in member 156 by pulling on knob 152, whereupon the arm 150 may be turned to a position opposite the other aperture. It may be latched in this position by releasing the knob to permit pin 154 to enter the aperture. In Fig. 11, cam portions 144 and 146 are in their inoperative positions, so that pawls 108 and 118 may operate spindle 24 without hindrance. By moving arm 150 from the position shown in Fig. 11 to the left so as to insert pin 154 in the left hand aperture, the pawls 108 and 118 will both be lifted from their ratchets by portions 144 and 146 sufficiently to permit spindle 24 to be manually turned.

A further feature of the apparatus shown in the drawings and one not affecting the mechanism according to the invention in its usual operation, is a known safety feature comprising a lever 160, best shown in Figs. 3 and 6, which hangs vertically from a pivot pin 162 (Fig. 7) fixed to a bracket 164 on the machine frame. The lever is bifurcated at its lower end. Normally, lever 160 is positioned as in Fig. 6 so that the end of extension 42 of lever 30 lies intermediate the prongs at the bifurcated end of the lever 160 so that the lever 30 is free to move up and down when permitted by levers 52 and 54. However, spindle 24 having moved the nut 25 a certain distance in either direction, an arm such as the one shown at 165 in Fig. 3, which is connected to the nut, moves against one or the other of a pair of collars 166 on a rod 168 which is pivotally connected to lever 160 and which is embraced by the lower end of arm 165. Consequently, when the lower end of arm 165 contacts the left collar 166, it swings lever 160 to the left, clockwise as viewed in Fig. 6, so that a notched surface 170 in the lower end of the right hand prong 172 of lever 160 overlies a land 174 at the rear end of the arm 42 to thereby prevent the lever 30 and extension 42 from delivering an impulse to either the A or B trains of mechanism. Similarly, if the spindle 24 has been turned to bring the lower end of arm

165 against the right hand collar 166, as viewed in Fig. 3, the left hand prong 176 of the lever 160, as viewed in Fig. 6, is moved so that its notch 170 overlies the land 174 of extension 42. Therefore, no impulse can be transmitted by lever 30 and extension 42 to either A or B trains of mechanism. With this arrangement, movement of the nut 25 is held within predetermined limits in either direction. Further movements beyond such predetermined limits, and instituted by the pattern means, will cause the arm 165 to engage one or the other of the collars 166 and thereby move either the prong 172 or 176 above the arm 42 as and for the purpose hereinbefore set forth. In order to return the nut 25 to a position within the limits determined by the collars 166, the spindle 24 must be manually turned by means of handle 147.

In order to maintain the lever 160 in the position of Fig. 6, except when the lever is moved by engagement of the arm 165 with one of the collars 166, the lever is provided with a plunger 180 having a tapered end 182 which is pressed into a corresponding notch 184 in the pin 162, on which the lever is pivoted, by a compression spring 186 (Fig. 7). Movement of the lever 160 in either direction, as viewed in Figs. 6 and 7, forces the tapered end 182 partially out of the notch 184. However, immediately upon disengagement of the collar 166 causing the lever 160 to turn, the tapered end 182 is forced to reseat itself in the notch 184 thereby returning the lever to the position of Fig. 6.

When it is desired to manually turn the spindle 24, handle 148 is shifted to the left from the position in which it is shown in Fig. 11 to put pin 154 in the left hand aperture 158 and thereby to disable both pawls 108 and 118. Thereupon, after manually engaging clutch teeth on the handle 147 with corresponding teeth (not shown) in a sprocket 204 also pivoted on shaft 149, rotation of the handle 147 turns the sprocket which in turn drives a sprocket chain 206 shown in dot-and-dash outline in Fig. 1. Chain 206 drives in turn a sprocket 208, which is shown diagrammatically in Fig. 1, as fixed to the spindle 24 to turn the spindle. When the handle 147 is released, a spring (not shown) disengages the clutch teeth in the handle from the teeth on the sprocket 204 so that movement of the spindle 24 by pawl 108 or pawl 118 will idly turn the chain without turning the handle. The spindle 24 also carries a notched disk 209 which is engaged by a detent 210 (Fig. 8) to maintain the spindle in the positions to which it is turned by the pawls 108 and 118.

The operation of the apparatus shown in the drawing will be obvious to those skilled in the art from the foregoing description but will be summarized for purposes of convenience as follows:

When the spindle such as the one shown at 24 is to be turned in the clockwise direction as viewed in Fig. 1, the pattern chain is operated so that a button on the chain operates lever 34 to move it out from under follower lever 30. The follower 28 is thereby permitted to follow the contour of cam 22 on main cam shaft 20. The tension of spring 50 acts through arm 44 and contact screw 48, latch lever 52 and latch lever 160 being in their inactive positions as shown in Figs. 5 and 6, to operate the train of mechanism A which includes the vertical link 88 and the pin 94. Operation of the mechanism A causes pawl 108 to rack spindle 24 in the clockwise di-

rection as viewed in Figs. 1, 9 and 10, while pawl 118 is lifted from its ratchet by cam portion 128 acting on lug 130 of pawl 118 due to the pivotal connection between pin 94 and the support 126 of cam portion 128 through link 96. Due to the fact that link 96 is rigid, cam portion 128 is moved by pin 94 through the action of spring 50 first to disable pawl 118 and then to positively release it through the action of cam 22 to stop the spindle 24 in the proper position.

Similarly, when the lever 64 is turned by the pattern means 40 the plate 78 on lever 64 also moves lever 34 from under lever 30. Thereby, not only is follower lever 30 released so that its follower 28 follows the contour of cam 22 but also shaft 72 is turned to turn arm 74 (Fig. 5) to shift link 58 and to thereby swing levers 52 and 54 clockwise as viewed in Fig. 5 to latch lever 44 and its train A and to release lever 45 and its train B. The rotation of cam 22 therefore permits lever 45 to move up in response to its spring 50 and to be moved down again by the cam 22 to thereby reciprocate the pin 95. Link 100 thereupon draws pawl 118 clockwise about spindle 24 to cause the pawl to drop in behind another tooth and link 102 draws cam portion 138 counterclockwise about spindle 24 to cause the cam portion to act on lug 140 to lift pawl 108. When the floating pin 95 thereupon reverses its direction of movement, the pawl 118 acts on its ratchet 120 to turn the spindle 24 counterclockwise as viewed in Fig. 12. The link 102 being rigid, the movement of cam portion 138 is reversed at the same time as that of pawl 118 so that pawl 108 is dropped down onto its ratchet 110 in time to stop the ratchet and spindle at the proper point.

Of course, the improvements specifically shown and described by which I obtain the referred to results, can be changed and modified in various ways without departing from the invention herein disclosed and hereinafter claimed.

What I claim is:

1. In a full-fashioned knitting machine, the combination of a racking means for a spindle comprising a pair of oppositely directed ratchet wheels and pawls therefor, a cam means and connections for transmitting impulses from said cam means to said pawls including two trains of mechanism, one connected to each pawl and a discriminating means for determining to which pawl an impulse from said cam means shall be delivered and having two bluffs both out of contact with any pawl when inactive and one bluff operated by one of said trains to prevent one pawl from operating while the one train operates the other pawl to rack its ratchet and the other bluff operated by the other train to prevent the other pawl from operating while the other train operates said one pawl to rack its ratchet, and means positively connecting said trains to the bluffs to draw them out of contact with the pawls after racking operations.

2. In a full-fashioned knitting machine, the combination of a racking means for a spindle comprising a pair of oppositely directed ratchet wheels and pawls therefor, a cam means and connections for transmitting impulses from said cam means to said pawls including two trains of mechanism, one connected to each pawl, a discriminating means for determining to which pawl an impulse from said cam means shall be delivered and having two bluffs both out of contact with any pawl when inactive and one bluff operated by one of said trains to prevent one

pawl from operating while the one train operates the other pawl to rack its ratchet, and the other bluff operated by the other train to prevent the other pawl from operating while the other train operates said one pawl to rack its ratchet, said trains being inelastically connected to the bluffs to draw them out of contact with the pawls after racking operations, a second discriminating means set to normally cause one of the trains to actuate a pawl to rack its ratchet and to keep the other pawl from acting, a pattern means and connections between the pattern and second discriminating means adapted to shift the second discriminating means to cause the other bluff and actuating pawl to become active. 15

3. In a full-fashioned knitting machine, the combination of a racking means for a spindle comprising a pair of oppositely directed ratchet wheels and pawls therefor, a cam means and connections for transmitting impulses from said cam means to said pawls including two trains of mechanism, one connected to each pawl, a discriminating means for determining to which pawl an impulse from said cam means shall be delivered and having two bluffs both out of contact with any pawl when inactive and one bluff operated by one of said trains to prevent one pawl from operating while the one train operates the other pawl to rack its ratchet and the other bluff operated by the other train to prevent the other pawl from operating while the other train operates said one pawl to rack its ratchet, said trains being inelastically connected to the bluffs to draw them out of contact with the pawls after racking operations, a second discriminating means set to normally cause one of the trains to actuate a pawl to rack its ratchet and to keep the other pawl from acting, a pattern means, connections between the pattern and second discriminating means adapted to shift the second discriminating means to cause the other bluff and actuating pawl to become active, the two trains of mechanism comprising each a member adapted and arranged to move up and down to deliver an operating impulse to one or the other of the pair of racking means and the second discriminating means comprising a pair of levers one of which normally retains one of said train members against upward movement, and pattern controlled means for swinging one of said levers to release said train member and to swing the other of said pair of levers to cause it to retain the other member. 45

4. In a full-fashioned knitting machine, the combination with a spindle, reversely arranged ratchets fixed to said spindle, a pair of pawls for actuating said spindle pivotally mounted thereon, bluffs for said pawls also pivotally mounted on the spindle, a lever reciprocated at desired times, a link pivotally and inelastically connecting said lever with the mounting of one of said pawls for operating it, a second link pivotally and inelastically connecting said lever with a bluff adapted to act on the other of said pawls to hold it away from its ratchet, a second lever reciprocated at desired times at which said first lever is stationary, a link pivotally and inelastically connecting said second lever with the mounting of said other pawl to actuate it, and a link pivotally and inelastically connecting said second lever with a second bluff adapted to act on said one pawl to hold it away from its ratchet. 70

5. In a full-fashioned knitting machine, the combination with a spindle having reversely arranged ratchets fixed thereto and pawls for the ratchets, of mechanism adapted to transmit oper- 75

ating impulses to said ratches comprising two different trains each one connected to a pawl for one of said ratches and each train having a spring actuated retracting movement and a power actuated forward movement, a discriminating mechanism comprising latching levers adapted to hold each an element of one train during said spring actuated movement and connected and arranged to hold their elements alternately against movement during said spring actuated movements, and pattern means adapted to control the initiation of said spring actuated movement and to control said discriminating mechanism to determine which latching lever engages its train element at a given time.

6. In a full-fashioned knitting machine, the combination with a spindle having reversely arranged ratchets fixed thereon and pawls for said ratches pivotally mounted on the spindle, of mechanism adapted to transmit operating impulses to said pawls comprising a discriminating means including bluffs one for each pawl, two different trains each one connected for racking one of said ratches and cam-and-follower means adapted to deliver operating impulses to said mechanism, said trains including each a pivoted member and a link pivoted to said member, a spring biasing said member to swing upward and connected thereto on the same side of the pivot of the member as the connection between the member and the link, a bell-crank lever also pivoted to said link, a pivot means moved to-and-fro by said bell-crank lever, links pivoted to the to-and-fro pivot means and pivoted in turn, one indirectly to a pawl and one directly to a bluff member for the other pawl, a pattern means, a pattern controlled means normally holding the follower part of said cam-and-follower means in the position to which it is moved by the high point of the cam part of such means and actuated by the pattern means to permit the follower part of such means to follow the contour of the cam, and a second discriminating means comprising pivoted levers adapted each to engage one of said train members, pattern controlled means normally holding said levers in positions in which one engages one of said pivoted train members without affecting the other pivoted train member while the other lever of the discriminating means is free of contact with either of the pivoted train members, said pattern means at times releasing said cam-and-follower means to cause it to initiate a racking impulse to turn said spindle and at other times both releasing the cam-and-follower means and operating said levers of the discriminating means to release the pivoted train member normally held by one of the levers and to hold the other pivoted train member to cause a racking impulse to turn the spindle in the opposite direction.

7. In a knitting machine, the combination of two trains of mechanism for delivering racking impulses from a cam means to a spindle and intended to operate only one at a time, said trains comprising each a member having an up-and-down movement at the times its train is operated, said members being spring operated on an up-stroke and power operated on a downstroke, a discriminating means comprising a pair of pivoted levers connected to swing in unison and held normally so that one of the levers engages one of said train members so as to prevent it from making an up movement while the other train member is free of the levers, and pattern operated

means for swinging said levers to reverse the relationship of the levers and members.

8. In a full-fashioned knitting machine, the combination of a cam, a pivoted lever oscillated by said cam on which a follower for said cam is pivoted, two trains of mechanism adapted to receive and transmit impulses from said lever and each including a lever member mounted to move in a plane parallel to the plane of movement of said lever, contact connections between said follower lever and said lever members arranged to transmit an operating impulse to either of said lever members in one direction as the cam follower moves from a low point of the cam to a high one, spring means biasing said lever members in the direction against said contact connections, and discriminating means including latch levers connected to move in unison and adapted to act one at a time on one or the other of said lever members to hold one member from responding to its spring bias.

9. In a full-fashioned knitting machine, the combination of a cam, a pivoted lever oscillated by said cam, a follower for said cam pivoted on said lever, two trains of mechanism adapted to receive and transmit impulses from said lever and each including a lever member mounted to move in a plane parallel to the plane of movement of said lever, contact connections between said follower lever and said lever members arranged to transmit an operating impulse to either of said lever members in one direction as the cam follower moves from a low point of the cam to a high one, spring means biasing said lever members in the direction against the contact connections, discriminating means including latch levers connected to move in unison and adapted to act one at a time on one or the other of said lever members to hold one member from responding to its spring bias, and means for shifting the latch levers to cause them to determine which lever member is to respond to an operation of said follower lever.

10. In a full-fashioned knitting machine, the combination of a cam, a pivoted lever oscillated by said cam on which a follower for said cam is pivoted, two trains of mechanism adapted to receive and transmit impulses from said lever and each including a lever member mounted to move in a plane parallel to the plane of movement of said lever, contact connections between said follower lever and said lever members arranged to transmit an operating impulse to either of said lever members in one direction as the cam follower moves from a low point of the cam to a high one, spring means biasing said lever members in the direction against said contact connections, discriminating means including latch levers connected to move in unison and adapted to act one at a time on one or the other of said lever members to hold one member from responding to its spring bias, a lever arranged to normally hold the follower lever in the position to which it is moved by the cam, and a pattern means for moving said holding lever to release the follower lever to follow the cam contour.

11. In a knitting machine, the combination of two trains of mechanism for delivering oppositely directed racking impulses from a cam means to a spindle and intended to operate only one at a time, said trains extending generally vertically, bluffs connected one to each said trains at their upper ends and adapted when one train operates to prevent the other train from interfering with the movement of the spindle, each train having

5 at its lower end a pivoted member having an up-and-down movement when its train is operated, and a discriminating means comprising a pair of levers pivoted to swing in a plane transverse to the planes of said up-and-down moving pivoted members and effective only one at a time but each adapted when in effective position to contact one of said up-and-down moving levers to hold it stationary while the other up-and-down moving lever and its train is free to move to transmit a racking impulse to said spindle.

10 12. In a knitting machine, the combination of two trains of mechanism for delivering oppositely directed racking impulses from a cam means to a spindle and intended to operate only one at a time, said trains extending generally vertically, bluffs connected one to each said trains at their upper ends and adapted when one train operates to prevent the other train from interfering with the movement of the spindle, each train having 15 at its lower end a pivoted member having an up-and-down movement when its train is operated, a discriminating means comprising a pair of levers pivoted to swing in a plane transverse to the planes of said up-and-down moving pivoted members and effective only one at a time but each adapted when in effective position to contact one of said up-and-down moving levers to hold it stationary while the other up-and-down moving lever and its train is free to move to transmit a racking impulse to said spindle, and a pattern actuated means for shifting said levers 20 of the discriminating means.

25 13. In a knitting machine, the combination with a cam shaft, a cam thereon, a cam follower for said cam, a pivoted lever on which said follower is pivotally mounted, said lever extending on the other side of its pivot from said follower and having two contacts thereon on said extension, a pair of trains of mechanism each including a lever member pivoted coaxially with said follower lever, springs on said lever members adapted and arranged to force them against said contacts and said follower against said cam, each 30 of said trains having connections for delivering an impulse from said cam.

35 14. In a full-fashioned knitting machine, the combination of a racking means for a spindle comprising a pair of oppositely directed ratchet wheels and pawls therefor, both said pawls being engaged with teeth of their ratchets to hold their ratchets when the spindle is to be stationary, and means for determining which pawl is to be effective when the spindle is to be moved, said last named means having two inelastic links and 40 bluffs pivotally connected to said links and rotatably mounted with respect to the spindle, both said bluffs being ineffective with respect to the pawls when the spindle is to be stationary but one of said links moving a bluff to disable one pawl at the time the other is to rack the spindle.
